Des. 210,442
Patented Mar. 5, 1968

210,442

COMBINED SCOREBOARD AND SIGN

Jacques Y. Foster, Des Moines, and Theron E. McCullough, Altoona, Iowa, assignors to Fair-Play Mfg. Co., Des Moines, Iowa, a corporation of Iowa

Filed July 25, 1967, Ser. No. 7,976

Term of patent 14 years

(Cl. D96—12)

Fig. 1

Fig. 4

Fig. 3

Fig. 5

Fig. 8

Fig. 7

We claim:

The ornamental design for a combined scoreboard and sign, substantially as shown and described.
